UNITED STATES PATENT OFFICE.

HELMUTH JOHN GAESS, OF PALISADE, NEW JERSEY.

COMPACT BOX.

Application filed July 29, 1926. Serial No. 125,633.

This invention relates to a compact box.

It has been the general practice to manufacture compact boxes from metals. There are certain undesirable features in the use of metals for such purpose. The metal boxes are relatively heavy and sometimes discolor the compact or become discolored themselves. The composition materials that are odorless have only been available for single compartment compact boxes due to the impossibility of permanently securing an ordinary hinge to such material. In addition, the usual hinge detracts from the beauty of the appearance of the box.

One of the objects of this invention is to provide a composition compact box. Another object of this invention is to provide a compact box having a hinge with no protruding parts and one that can be secured in a substantial manner to the composition. Still another object of this invention is to provide a compact box so hinged as to permit of the opening to any desired angle of the various compartments all at the same time and to permit of a ready closing thereof. A further object is to provide a compact box made up of sections that can be assembled in various multiples and in different ways.

Referring to the drawings:

Figure 1 is a cross sectional view of a compact box adapted to contain in the lower portion a compact and in the upper portion a mirror.

Figure 2 is a sectional view of a compact box adapted to contain in the upper portion a mirror, in the central portion a compact and in the bottom portion a compact.

Figure 3 is a broken plan view of the compact box.

Figure 4 is a cross sectional view of a modified form of compact box.

Figure 5 is a perspective view of the modified form of compact box.

Figure 6 is a detail cross sectional view of the modified form showing the hinge portion.

Figure 7 is a detail cross-sectional view of the combination pivot and fastening means.

In carrying out my invention, I provide a compact box 1 made of composition and comprising two or more sections.

In Figure 1, I show compact box 1 having top section 2 and bottom section 3.

In Figure 2, I show a compact box having top section 2, bottom section 3 and central section 4.

The top section 2 has lip or rim 5 to fit within bottom section 3 or central section 4. Rims 5, 5', functioning to prevent any loose powder from being shaken out after the box is closed and also to furnish a support and seat so that the two parts of the box will be firmly held together when closed and to prevent the springing of the hinges 6, 6', when closed in case it is dropped.

Hinges 6, 6', are formed of thin plates or sheets of metal having the outside outer edge shaped to conform to the outline of the box and operate in slots 7, 7', cut into the edges of the sections of box 1.

In the case of a two section box, hinges 6, 70 have two drilled holes 8, one in the upper and the other in the lower portion and centrally of said portions to receive pins 9.

In the case of a built up compact box such as shown in Figure 3, the hinges 6' are similar 75 in every respect except that for each section there is a corresponding portion in the hinge having a hole such as 8' for the additional section to accommodate a pin.

The pins 9, are preferably embedded in 80 the composition by means of a cement although I have found that a single pin might be utilized and the ends upset to prevent falling out.

I provide a metallic pin 11 having a small 85 bulb base 12 as a snap lock co-operating with split socket 13.

In the modified form of compact box 1 the bottom section 3' is pivotally connected to section 4' and adapted to swing around horizontally as shown in Figures 4 and 5. Pivot 11' functions also as a snap lock having a ball tip 12' co-operating with a split socket 13' carried by the top section 2'. Rim 5'' is omitted from the bottom of section 4'. The 90 hinges 6'' are the same except that they are formed from a single sheet of metal connected by a back piece 14 which carries a prong 15 to snap into a depression 16 in the rim of section 3' when the bottom section 3' is closed.

It will be noted that the hinge designed does not move but that the pin rotates in the hinge as the section is lifted. This form of hinge does not protrude from the box and furnishes a relatively strong support for its 105 small size and does not detract from the appearance of the box as it is almost invisible, only two thin strips of metal showing and which strips are flush with the edges of the box. The construction shown permits of the 110

utilization of non-odorous composition material which will not retain a screw and to which metal cannot be readily riveted. Although I have shown hinges 6, 6', 6'', as 5 being made of metal, yet they can be made of composition or other material.

What I claim is:

1. A container having a top and bottom section, parallel channels cut in the edges of 10 said sections, plates in said channels, holes in said plates in alignment with the holes of the adjacent plate, pins secured to each of said sections and passing through said aligned holes, said pins journaled in said 15 holes to rotate therein.

2. A sectional compact box, parallel channels cut in the edges of said sections, plates in said channels, pins secured to said sections, said pins passing through said plates 20 at right angles thereto and having their axes of rotation in said plates to permit of movement of one section with respect to the other section without movement of the plates.

3. A sectional compact box, parallel channels cut in the rear of said box, parallel plates in said channels, said plates having frictional contact with the side walls of said sections, pins secured to said sections and adapted to 25 rotate therewith, aligned holes in said plates

forming the axes of rotation for said pins 30 and sections.

4. A sectional compact box, two parallel channels cut in the edges of said sections, two parallel plates in said channels, holes in each of said plates, said holes in alignment 35 with the holes in the same plate and with the corresponding holes in other plate, each of said sections pivotally connected to said plates by pins through said holes to permit of rotation of each section with respect to said 40 plates and independent of the movement of any other section.

5. A compact box comprising sections, parallel channels cut in the rear edges of said sections, at right angles to the plane of 45 the sections, parallel plates in said channels, a hole centrally in each plate for each section, the hole of each plate in alignment with the corresponding hole in the other plate, pins journaled in said holes for each section 50 to pivotally connect the sections to said plates, said plates being immovable with respect to one of said sections.

Signed at New York, in the county of New York and State of New York this 16th day 55 of July, A. D. 1926.

HELMUTH JOHN GAESS.
